WINDOW STRUCTURE

Bernard E. Mendelsohn, Newton, Mass. (9 Harvey
Window Corp., 309 Main St., Watertown 72, Mass.)
Filed May 16, 1956, Ser. No. 585,352
4 Claims. (Cl. 160—90)

The present invention relates to a storm window and in particular to a novel construction of a storm window and frame therefor.

The present invention provides a novel structure for a storm window in which there is provided a combination of a storm window and screen. In this structure means are provided by which the window may be readily disassembled for cleaning purposes. In this operation, side runners for the window sash and screen elements are removed and the window sashes are pivoted inwardly at an angle to the window frame so as to permit an individual to clean both sides of the window pane. In this structure, there is provided a hinging member to facilitate the pivoting of the window pane to a desired cleaning position. This hinging element is so constructed as to permit the window pane to be entirely removed from the frame. Similarly, the screen member may also be entirely removed from the frame, if desired. Such structure will obviously avoid the requirement that windows be cleaned from the outside by sitting on the window sill or by using ladders, which operations are, of course, quite dangerous in nature.

The structure of the present invention further provides a unit which is relatively inexpensive to manufacture, but which has a minimum of operative elements, thus, providing a rather fool-proof operation which is quite unlikely to become broken or otherwise inoperative.

The present invention also provides a structure in which the frames and the window panes interengage in a locked position when the panes are closed. To open the window from the inside, the operator need only press the inside window outwardly to disengage the interengaged element and then slide the window pane upward. A similar interengaging element is used for the screen element and this may also be unlocked by a similar operation. Both the screen and the window pane, however, can not be unlocked from the outside, as there is no means by which the screen or pane may be pressed outwardly from the outside. These and other objects of the present invention will be more clearly understood when considered in connection with the accompanying drawings in which:

FIGURE 1 is a plan view of the invention,

FIGURE 2 is a cross sectional view taken substantially along the line 2—2 of FIGURE 1,

FIGURE 3 is a cross-sectional view showing the invention in an arrangement whereby the window may be pivoted to a cleaning position,

FIGURE 4 is a cross-sectional view taken along the line 4—4 of FIGURE 1,

FIGURE 5 is a fragmentary perspective of a lower corner of the frame assembly, and

FIGURE 6 is a fragmentary cross-sectional detail of a window sash.

Referring to the drawings, there is illustrated a storm window having an outer frame extending about four sides with each side joined to the adjacent side by suitable means and preferably at an angle of 45°. This outer frame 1 is provided with its lower side or bottom 7 having a cross section as illustrated in FIGURE 5. This lower side 7 has in its cross section a vertically extending flange 2 with several horizontally-extending flanges 3, 4 and 5. The lowermost horizontally-extending flange 3 forms an outside apron of the frame of the storm window

2

and extends entirely about the frame, thus providing a means for securing the frame to the window casing. If desired, nails or screws may be driven through the flange 3 into the window casing to secure it in place. The element 4 provides a strengthening flange, while the element or flange 5 extends inwardly a substantial distance beyond flange 3 or 4. Projecting ribs 6, 7', 8 and 9 may be provided on the flanges 4 and 5 for additional strengthening purposes and also to provide channels for uses not coming within the scope of the present invention. The inner end of the flange 5 terminates in an upwardly-extending lip 10. There is also provided a hook member 11 which extends upwardly from the central portion of flange 5. The upwardly or vertically-extending flange 2 extends into an upwardly-extending lip 12 which projects upward and beyond the horizontal flange 5. If desired, lip 12 may be provided with a center section 13 having a slight angular bend in it primarily for purposes of decoration. The frame has sides 14 and 15 and a top 16 which are similar in cross section to bottom 7, except that they do not have a hook member 11.

Positioned upon the bottom 7 is the locking element 18. This locking element 18 extends from side 14 to side 15 and comprises in cross section two side walls 19 and 20 interconnected continuously by a top 21 with the top 21 inclined downwardly towards the outside of the locking member 18. Side 20 is longer than the side 19, while the side 19 is provided with a longitudinally-extending, hook-like flange 22 extending outwardly and downwardly at its base. This locking element 18 is also provided with two upwardly-extending flanges 23 and 24 with the upper ends of the flanges 23 and 24 each provided with a barb-like upper edge as illustrated at 25 and 26 respectively. These barb-like elements 25 and 26 may extend continuously along the length of the upwardly-extending flanges 23 and 24, or may, if desired, be intermittent in such a manner as to engage with the screen and window pane in the manner hereinafter described.

The locking element 18 has its side walls 19 and 20 of a sufficient and proper length to interengage the sides of the bottom 7. Thus, the flange 22 and side 19 cooperate to engage the upwardly-extending lip 12 at its extreme top end, while the side 20 extends downwardly to engage the flange 5 adjacent the upwardly-turned lip 10. By this arrangement, locking element 18 may be securely held in position between the sides 14 and 15 and the lip 12 and lip 10. This locking element 18 may, however, be removed for the purposes hereinafter described.

To permit removal of this locking element 18, sufficient leeway should be provided at the ends to permit it to be pivoted upward for removal when desired. Secured to the sides 14 and 15 are a pair of runners 30 and 31. These runners are secured between the lips 12 and 10 on the side 14 and 15 by screws or other suitable means. These opposite parallel runners 30 and 31 are provided with two substantially equal longitudinal channels 33 and 34 formed respectively by the channel flanges 35, 36 and 36, 37. These channel flanges 35, 36 and 36, 37 extend downwardly to a joint just short of the midpoint of the window frame and provide fixed channel runners for the window panes and shades hereinafter described.

Additional side runners 38 and 39 form continuations respectively with side runners 30 and 31. These side runners 38 and 39 are identical in cross section with the side runners 30 and 31. They are, however, removable and are secured in position by engagement with the lips 12 and 10 of the side frames 14 and 15 respectively which hold them from accidentally being removed in a sideway direction and by engagement at their ends with the side runners 30 and 31 and the bottom locking member 18. In order to facilitate removal of these side runners 38

and 39, the tops are preferably bevelled towards the base of the runners, while the bottoms which interengage the locking member 18 are provided with notches 40 and 41 in the rear wall 42 of the side runners. These notches 40 and 41 fit over the upwardly-extending flanges 23 and 24, thus providing a snug and engaging fit between the side runners 38 and 39 and the locking member 18. This engaging fit, however, is such as to permit removal of the side runners 38 and 39 when desired. It is to be noted that the flange 44, which is a continuation of the flange 37, is positioned outside of the flange 24 when the side runners are in position. Flange 45, which is a continuation of flange 36, is aligned with the flange 23; while flange 46, which is a continuation of flange 35, is positioned just inside of flange or lip 12.

Within this frame assembly there is positioned an upper window sash 50, a lower window sash 51 and a screen 52. These elements 50 and 51 are similar in structure to one another and each are provided with a frame having a cross section in the shape of an H. In this structure the cross section has two side legs 53 and 54 and a cross member 55. This cross section is continuous all about the four sides of the frame which enclose the glass panel 56. The glass panel 56 is secured at its edges between the inner portions of the leg 53 and 54. The four elements, having this H cross section which comprise each of these frames, are secured together at their ends which are preferably bevelled at an angle of 45° by any suitable means, such as an L-shaped clip having one leg adjacent the outer surface of the cross member 55 on one side of the frame and the other leg adjacent the outer surface of the cross member 55 of the adjacent side. The ends 102 of this L-shaped clip 101 are bent inwardly in a lip which engage an opening in the surface 55 of the cross member. These clips may be rigidly secured in place by suitable means, such as by punching holes 100 in the leg or side 53 so that the periphery of the hole is flared inwardly engaging the L-shaped clip. The lowermost side of these frames 50 and 51 have their outer leg 54 provided with a barb 59 at their lower edge. This barb 59 is adapted to engage the barb 26 when the lower window sash 51 is in a down and locked position. The lower window sash 51 is tensioned in an inward direction by the spring 60. This spring 60, which is a leaf spring, having its end 61 projecting through the side frames of the window sash in the inner portion of the leg or flange 53. The spring 60 normally engages the inside surface of the flanges 37 and 44 and tensions thereby the window sash 51 inwardly to a point at which the inner portion 63 of the leg 54 of the side portions of the window frame ride in face to face contact with the outer surfaces of the flanges 37 and 44. This arrangement of the window sash 51 and the flanges 37 and 44 is identical on both sides of the window. Thus, when the lower window sash 51 is in an up or partially up position, generally indicated by the dotted outline 64, the side 54 of the frame is aligned with the flange 24. When, however, the window sash is pulled all the way down to a closed and locked position, the barbs 59 and 26 engage with one another and are held in this position by the tension of the spring 60. The top window sash is similar in structure and has a similar cross section and spring provision.

This leaf spring on the top window sash 50 tensions against the flanges 35 and 46 in such a manner as to also tension the top window sash in an inward direction. This top window sash is, however, not provided with engaging barbs as is the bottom, as such locking members are not ordinarily necessary for the upper window sashes in a storm window arrangement. Sandwiched between the top and bottom window sashes 50 and 51 is the screen 52. This screen is provided with the frame 67, which frame has a cross section as illustrated in FIGURE 2. This cross section has parallel leg members 68 and 69 joined together at their inner end by the cross member 70. A pair of ribs 71 may be provided on

the inner surfaces of the legs 68 and 69 for strengthening purposes. Leg 68 continues inwardly forming a channel 72 between the section 70 and the lip 73. The lip 73 is angularly arranged with respect to the section 70 forming a channel 72 with a restricted opening. The screen which may be made of any suitable material such as aluminum screening has its edges secured within this channel 72 by suitable means which may include a resilient cord member forced into the channel 72 about the periphery of the screen. The lower end of the leg 69 of the bottom cross member of this screen 52 is provided with a barb 74 which is adapted to engage the barb 25 when the screen is in a down and locked position.

15 This screen 52 is also provided with a spring 77 at each side secured to the screen in a manner similar to that as described in connection with the spring 60. This spring 77 tensions the screen 52 inwardly also in a manner similar to that described in connection with the window sashes 50 and 51. Thus the screen 52 may be moved from an open or partially open position into a closed and locked position in the manner similar to that described in connection with the locking operation of the top and bottom window sashes 50 and 51. The screen 52 may be locked in an up position, if desired, in the manner similar to that described in connection with the locking of the window sash 50 in an up position.

20 The above arrangement described provides a structure in which a locking mechanism may be eliminated if desired. It further provides, however, structure in which the window may readily be unlocked by merely pushing the window sash slightly outwardly to disengage the barbs against the tension of the spring and thereafter raising the window sash upwardly until the barbs are no longer engaged with one another.

25 30 35 In the present invention there is also provided a means for pivoting the window sashes from a vertical position to an angular position extending inwardly of the sash so as to readily permit the washing of the inside as well as the outside of the windows. The structure also provides means by which the window sashes may readily be removed for repair or cleaning if so desired. In this structure and operation the locking member 18 is removed from engagement with the sash at the removal of the side channels 38 and 39. When the locking element 18 is removed, the window sashes are then slid downwardly from their up position so that they come into engagement with the hook member 11. In this position, the upper ends of the window sashes are free of the fixed channels 30 and 31 and are thus readily pivoted into a position as illustrated at 80 (FIG. 3). In this position they may be cleaned or, if desired, removed from the window frame structure to permit repair or more extensive cleaning. In this manner either or both window sashes 50 or 52 may readily be cleaned without the requirement of going outside of the house or structure in which the window is located.

40 Having now described my invention, I claim:

45 50 55 60 65 1. A storm window having a rectangular frame, removable runners positioned at each side of said frame, upper and lower window sashes and a screen slidably engaged by said runners, a removable locking member positioned over the bottom of said frame and for locking said lower window sash in a closed position, and means positioned below and hidden by said locking member and forming a pivotal support for said window sashes at the lower edge thereof when said locking member and runners are removed.

70 75 80 85 90 95 2. A storm window having a rectangular frame, removable runners positioned at each side of said frame, upper and lower window sashes and a screen slidably engaged by said runners, and a longitudinally-extending flange projecting upwardly from the bottom of said frame with an arcuate upper edge, a hook formed in the lower edge of said lower window sash pivotally engaging said

arcuate upper edge and thereby pivotally supporting said lower sash when the runners are removed.

3. A storm window as set forth in claim 1 wherein said removable locking member for locking the lower sash comprises an upwardly-projecting flange having a barbed upper edge and a barb on the lower edge of said lower sash adapted to yieldably engage barbed upper edge.

4. A storm window having a rectangular frame with runners positioned at each side and interconnecting upper and lower cross members, upper and lower window sashes having side edges slidably engaged by said runners, said edges adapted to be moved within said runners in a plane normal to said window sashes, spring means biasing said window sashes inward of said frame, 10

5

and locking means comprising interengageable barbs mounted on the lower cross member of said frame and on said lower window sash for locking said lower sash closed when said lower window sash is down and biased inwardly by the spring means, said locking means being inoperative when said lower window sash is pushed outwardly against the bias of the spring means.
